CLAIM

The ornamental design for a metal clad switchgear, substantially as shown and described.

DESCRIPTION

FIG. 1 is a perspective view of a metal clad switchgear illustrating my new design;

FIG. 2 is a front elevational view thereof;

FIG. 3 is a side elevational view thereof, the other side being a mirror image; and,

FIG. 4 is a top plan view thereof.

FIG. 1

FIG. 4

FIG. 2

FIG. 3
